Charles D. Stevens

UNITED STATES PATENT OFFICE.

CHESTER D. STEVENS, OF MENDOTA, ILLINOIS.

IMPROVEMENT IN APPARATUS FOR EVAPORATING SACCHARINE JUICES.

Specification forming part of Letters Patent No. 34,991, dated April 15, 1862.

To all whom it may concern:

Be it known that I, CHESTER D. STEVENS, of Mendota, in the county of La Salle and State of Illinois, have invented a new and Improved Evaporating Apparatus for Boiling and Reducing Sugar-Cane Juice; and I do hereby declare the following to be a full, clear, and exact description of the same, reference being had to the annexed drawings, making part of this specification, in which—

Figure 3 is a top view thereof; Fig. 2, a vertical longitudinal section on the line K K, and Fig. 1 a side elevation.

The object of my invention is to economize fuel in the reduction of sugar-cane juice to sirup by a novel application of steam to that purpose.

The following description of my invention will enable any one skilled in the arts to which it appertains to make and use the same.

Like letters of reference represent corresponding parts of the different figures of the drawings referred to.

C is an ordinary steam-boiler for the purpose of generating the steam. Over this boiler a pan, B, is arranged, in which the juice is first boiled and skimmed, and which is fitted with a series of steam-tight pipes, X X and Y Y, which pipes communicate with the boiler through the agency of the pipe F.

A represents the evaporating or reducing pan. It is fitted with a series of steam-tight pipes, X X and Y Y, and arranged above the boiler and below the pan B, and at the side of both, in the manner shown, so that the juice may be drawn from the boiling-pan to the reducing-pan through a pipe or leader, H, fitted with some kind of valve, and so that the pipe E, which unites the series of pipes in the pan A with the boiler, will incline from said series of pipes to the boiler. There is but one reducing-pan shown in the drawings; but there may be two or more arranged in the

same relation to the boiling-pan and steam-boiler. These pans may be made in any suitable form and of any suitable material, and they may be fitted with any convenient arrangement of pipes, which should, however, be provided with blow-cocks, as at J and G, to let out the air when the steam is let in. Now, when the steam is let in the pipes condensation commences, which, if there were no means of issue, would soon fill them with water of condensation, thus stopping the process of evaporation and reduction, for the condense-water would soon become as cold as the contents of the pans; and if the pans were arranged below the boiler or on the same horizontal plane with it the water of condensation would have to be blown or drawn out of the pipes, which would occasion a loss of heat, and consequently of fuel equal to the amount of heat contained in the water so drawn or blown out. To avoid this loss of heat by blowing out the condense-water, and the obstruction of the process resulting from the choking of the pipes with it, I arrange all the pans above the boiler and the pipes in them so as to incline a little toward the pipes F and E, communicating with the boiler. By these means the water of condensation falls back into the boiler as fast as it is formed, thus saving the fuel and increasing the efficiency of the apparatus by making the entire surface of the pipes effective.

Having now described the manner of constructing and operating my invention, I claim and desire to secure by Letters Patent—

The arrangement and construction of the boiling and evaporating pans in relation to each other and to the steam-boiler C, substantially in the manner described.

CHESTER D. STEVENS.
